UNITED STATES PATENT OFFICE

110,017

DESIGN FOR A COMBINED TABLE AND RADIO SET

Daniel J. Crowley, Grosse Pointe, Mich.

Application March 14, 1938, Serial No. 75,812

Term of patent 14 years

To all whom it may concern:

Be it known that I, Daniel J. Crowley, a citizen of the United States of America, residing at Grosse Pointe, in the county of Wayne, and State of Michigan, have invented a certain new, original, and ornamental Design for a Combined Table and Radio Set, of which the following is a specification, reference being had therein to the accompanying drawing, forming a part thereof, wherein:—

The single figure illustrates a perspective view of a combined table and radio set embodying my design.

The design of combined table and radio set is symmetrical about its vertical axis in that the side of the set opposite to the side shown in the drawing is the same in appearance, with the exception that the opening exposing the graduated dial is omitted.

I claim:

The ornamental design for a combined table and radio set substantially as shown and described.

DANIEL J. CROWLEY.
